DESIGN FOR A TRANSCRIBER FLOOR SWITCH

Robert L. Stone, Guilford, Conn., assignor to The
Soundscriber Corporation, New Haven, Conn.,
a corporation of Connecticut

Application August 23, 1945, Serial No. 121,592

Term of patent 14 years

(Cl. D26—13)

To all whom it may concern:

Be it known that I, Robert L. Stone, a citizen
of the United States, residing in the town of
Guilford, county of New Haven, and State of
Connecticut, have invented a new, original, and
ornamental Design for Transcriber Floor Switch,
of which the following is a specification, refer-
ence being had to the accompanying drawing,
forming a part thereof.

Fig. 1 is a top plan view of the transcriber floor
switch showing my new design.

Fig. 2 is a front view of the same.

Fig. 3 is a side view of the same.

I claim:

The ornamental design for a transcriber floor
switch, as shown.

ROBERT L. STONE.
